TAP CHANGING SYSTEM

Louis F. Blume and Salvatore Minneci, Pittsfield,
Mass., assignors to General Electric Company,
a corporation of New York

Application April 17, 1946, Serial No. 662,795

8 Claims. (Cl. 323—43.5)

1

This invention relates to electric circuits and more particularly to improvements in load-ratio-control circuits.

As here used the term "load-ratio-control" means the control or variation of the ratio of a transformer while it is under load by changing tap connections to at least one of its windings. In such circuits there is at least one switch or contactor which performs an arcing or current interrupting duty and it is this arcing duty contactor which usually has the shortest operating life of any part of the circuit, that is to say, it requires more frequent servicing than any other part of the circuit, with the result that it is usually necessary to shut down the transformer periodically for the purpose of servicing the arcing contactor.

In accordance with the present invention there is provided a novel load-ratio-control circuit in which the arcing duty is divided up among a plurality of switches or contactors and in which the major part of the arcing duty is performed by a switch which is connected into the circuit by way of an auxiliary insulating transformer. This makes it possible to select the ratio of the insulating transformer such as to give optimum current and voltage values to be ruptured by the arcing duty contactor. Furthermore, the arcing duty contactor, being in a separate circuit which is insulated from the main circuit by means of the insulating transformer, can be made readily accessible from outside the transformer and it can be serviced and even replaced while the main transformer is in operation.

An object of the invention is to provide a new and improved electric circuit.

Another object of the invention is to provide a new and improved load-ratio-control circuit.

A further object of the invention is to provide a new and improved arcing duty switching arrangement for load-ratio-control systems.

The invention will be better understood from the following description taken in connection with the accompanying drawing and its scope will be pointed out in the appended claims.

Referring to the single figure of the accompanying drawing, which is a diagrammatic illustration of an embodiment of the invention, there is shown therein a main transformer winding 1 which is provided with four taps 2, 3, 4, and 5. These taps are connected to separate ratio adjuster switches 6 and 7, that is to say, the ratio adjuster switches each have relatively fixed contacts corresponding in number to the taps of the main winding and these fixed contacts are connected

2

respectively to the different taps. The ratio adjusters 6 and 7 also have their movable contacts for selectively engaging their fixed contacts and these movable contacts are connected by way of branch circuits 8 and 9 respectively to a conductor 10 which leads to a terminal 11 for the winding 1. The other terminal for the winding 1 is indicated at 12.

The ratio adjusters 6 and 7 are ordinarily non-arching duty type switches which are typically placed in a separate sealed compartment of the conventional transformer steel tank and they are ordinarily submerged under cooling and insulating liquid such as mineral oil. It is therefore necessary to provide some means for interrupting the current in whichever ratio adjuster is to be operated prior to such operation so that there will be absolutely no arcing at its contacts when its movable contact is actuated from one fixed contact to the next. This is accomplished by means of a split reactor 13 whose two halves are connected respectively in series in the branch circuits 8 and 9 and a switching system comprising a pair of non-arching duty transfer switches 14 and 15 and three properly interlocked switches 16, 17 and 18 which selectively perform the current interrupting or arcing duty of the system. Switch 17 is connected into the circuit by means of an insulating transformer 19.

Transfer switch 14 is connected in the branch circuit 8 between the conductor 10 and one-half of reactor 13 and in series with the ratio adjuster 6. Similarly, transfer switch 15 is connected in the branch circuit 9 between the conductor 10 and the other half of reactor 13 and in series with the ratio adjuster 7. The switch 16 is normally closed and it is connected across the switches 14 and 15 in series, that is to say, it is connected between the branch circuits 8 and 9 on the side of the reactor 13 to which the switches 14 and 15 are connected and not on the side of the reactor to which the ratio adjusters 6 and 7 are connected. Connected in parallel circuit relation with the switch 16 is a circuit containing the primary winding of the insulating transformer 19 and the switch 18 in series. The switch 17 is connected across the terminals of the secondary winding of the insulating transformer 19 and this secondary circuit is grounded as at 20. In this system ninety per cent or more of the entire arcing duty is performed by the contactor or switch 17. Consequently, the switches 14, 15, 16, and 18 may also be located inside the same compartment with the ratio adjusters 6 and 7 and under its cooling

and insulating liquids as they will require very little servicing and should have substantially as long an operating life as the non-arcing duty ratio adjusters 6 and 7. The arcing duty contactors 17 may very well be a magnetic blowout type air break switch which is known to have a long operating life.

The various switches are all interlocked and driven by a suitable operating mechanism which is shown by way of example as being powered by a motor 21, although it will of course be understood that the mechanism could be hand-cranked if desired. The motor 21 may be started, stopped and reversed in any well known manner and it may be either manually controlled by push buttons or it may be automatically controlled in response to any suitable operating condition of the circuit of the main winding 1. Through a set of bevel gears 22 the motor 21 drives a Geneva gear driver 23 having a pair of pins facing in opposite directions and displaced 180 degrees from each other, which pins are adapted to engage respectively Geneva gears 24 and 25 which are mechanically connected through electrical insulating couplings 26 and 27 to the movable contacts of the ratio adjusters 6 and 7. The Geneva gear driver 23 makes one complete revolution for one complete cycle of operation of the system. The switch or contactor 16 is driven by a cam member 28 through another set of gears 29 and, similarly, the switch 18 is driven by a cam 30, the cams 28 and 30 being operated at the same speed so that they make two complete revolutions for each complete cycle of operation of the system. Driven by reduction gearing 31 from the shaft which drives the cams 28 and 30 are another pair of cams 32 and 33 for operating respectively the transfer switches 14 and 15. These cams operate at half the speed of the cams 28 and 30 so that they make one full revolution for each complete cycle of operation of the system. The main arcing duty contactor 17 is driven by a separate operating cam 34 at the same speed as the cams 28 and 30 so that it makes two complete revolutions for each full or complete cycle of operation of the system.

The operation of the illustrated embodiment of the invention is as follows: The system is shown in its so-called half-cycle or bridging position. This is characterized by having the ratio adjusters 6 and 7 connected to different, although electrically adjacent, taps. As shown, ratio adjuster 6 is connected to tap 2 and ratio adjuster 7 is connected to tap 3. The reactor 13 is in effect connected directly across or between the taps 2 and 3 through the ratio adjusters 6 and 7 and the transfer switches 14 and 15 so that it acts as an autotransformer and makes the voltage of the conductor 10 and the terminal 11 equal to the voltage of a point on the winding 1 which is half way between the taps 2 and 3. Load current for the winding which flows through the conductor 10 divides equally in the two halves of the reactor so that there is substantially no voltage drop in the reactor by reason of load current. There is, however, a current which circulates in the reactor due to the voltage difference between the adjacent taps 2 and 3 and this circulating current is limited by the magnetizing reactance of the reactor 13.

Assume now that the motor 21 is operated in such a direction as to cause the cams 28, 30, 32, 33, and 34 and the Geneva gear driver 23 to rotate in the directions indicated by their associated arrows. The first thing that happens is

that transfer switch 14 is opened by cam 32. There is substantially no arcing duty on this switch because switch 16 is still closed so that all of the current which has been flowing through the switch 14 from the upper half of the reactor 13 through the conductor 8 will now flow through the switch 16 and then through the conductor 9 and the switch 15 and out through the conductor 10 as before. As the motor continues to turn, the next switch to open is the switch 18. Here again there will be negligible arcing duty because the short-circuited insulating transformer 19 is connected in parallel with the switch 18 through the still closed switch 16. Consequently, the recovery voltage on the switch 18 will merely be the voltage drop of one-half the current for the main winding flowing through the leakage reactance of the insulating transformer 19 and obviously by well known design principles this leakage reactance may be made very low. Continued operation of the motor in the same direction will next cause the cam 34 to open the main arcing duty contactor 17. This opens the secondary circuit of the insulating transformer 19 and in effect interposes the magnetizing or exciting reactance of the insulating transformer 19 into the path for the current which flows through the ratio adjuster 6 and the upper half of the reactor 13.

At this point it should be explained that the insulating transformer 19 may either be a step-up or a step-down transformer; that is to say, it can either have a higher secondary current and a lower secondary voltage than the corresponding quantities of its primary winding or vice versa so that the optimum values of current and voltage from the point of view of arcing duty for any particular contactor 17 may readily be obtained.

The recovery voltage on the arcing contactor 17 is proportional to the voltage drop caused by the current in the ratio adjuster 6 flowing through the magnetizing reactance of the insulating transformer.

As the motor continues to operate, the cam 30 will next open the switch 18 and here again the arcing duty is relatively slight as this switch merely has to interrupt the exciting current of the insulating transformer 19. After the switch 18 has been opened it will be seen that the current in the branch circuit 8 is entirely interrupted so that ratio adjuster 6 may now be operated with no arcing at its contacts. Consequently the next operation is the movement of the ratio adjuster 6 counterclockwise one step so as to make connection with the tap 3. During this time all of the current of the winding 1 is being carried through the ratio adjuster 7 and the branch circuit 9 and this position of the system is known as its quarter-cycle position. This is ordinarily but a temporary position or condition of the system and the system is ordinarily not designed for continuous operation in this position. The voltage of the terminal 11 in the quarter-cycle position will not be quite equal to the voltage of the tap 3 because of the relatively high regulation in one-half of the reactor 13 through which all of the load current must pass. Consequently, the control of the system is ordinarily provided with an interlock (not shown) so that the system cannot be stopped in its quarter-cycle position but will continue on for a complete half cycle of operation before stopping. Therefore, the motor drive 21 continues operating with the result that first

switch 18 recloses, thus connecting the primary winding of the insulating transformer 19 between the branch conductors 8 and 9 or, in other words, across the switches 14 and 15 in series. Next the arcing contactor 17 recloses, thus in effect short-circuiting the insulating transformer, then the switch 16 recloses, thus in effect short-circuiting the leakage reactance of the insulating transformer 19 and finally the transfer switch 14 recloses. This has resulted in a complete rotation of the cams 28, 30, and 34, a half rotation of the cams 32 and 33 and a half rotation of the Geneva gear driver 23 and has placed the system in its full-cycle position in which the load current all flows through the tap 3 and divides equally between the two branch circuits 8 and 9 and the two halves of the reactor 13 and the voltage of the terminal 11 is substantially equal to the voltage of the tap 3.

It will be noted that in any normal or continuously operating position of the system, that is to say, in either its half-cycle or full-cycle position, the primary winding of the insulating transformer 19 is short-circuited by the switch 16 so that there is no voltage across this primary winding. At the same time it will be noted that the secondary circuit of the insulating transformer 19 is grounded at 28. Consequently, there is neither current flow through the switch 17 nor is there any voltage to ground of this circuit. Consequently, the arcing contactor 17 can be easily and safely serviced and even entirely removed from the system for such servicing while the transformer is in normal operation. Therefore, if desired, the arcing contactor 17 may be made of the conventional draw-out connection type which is well known in switch-gear practice. In other words, its electrical connections may be in the nature of plug and socket connections so that the entire contactor will be readily, in effect, plugged in or unplugged from the transformer.

A reverse operation of the motor drive from that previously described will of course first cause the opening of the transfer switch 15 and then the switches 16, 17, and 18 will open in the order mentioned which is the same order as has already been described, with the result that the current will be interrupted in the ratio adjuster 7 and this ratio adjuster will then move clockwise so as to make connection with the tap 2. In other words, operation of the system in the opposite direction will cause a half cycle of operation so as to change the voltage of the terminal 11 from midway between the taps 2 and 3 to the voltage of tap 2 which is the opposite full-cycle position to that which was previously described in which the voltage of the terminal 11 is changed to the voltage of the tap 3.

While there has been shown and described a particular embodiment of this invention, it will be obvious to those skilled in the art that various changes and modifications can be made therein without departing from the invention and therefore it is aimed in the appended claims to cover all such changes and modifications as fall within the true spirit and scope of the invention.

What we claim as new and desire to secure by Letters Patent of the United States, is:

1. In combination, a transformer winding having a plurality of taps, a pair of ratio adjuster switches for selectively making connection to said taps, a terminal for said winding, a pair of transfer switches connected to said terminal, a split reactor each half of which is serially connected

between a different ratio adjuster and a different transfer switch, an insulating transformer, a disconnecting switch for connecting the primary winding of said insulating transformer across said transfer switches in series, and an arcing contactor connected across the secondary winding of said insulating transformer.

2. In combination, a transformer winding having a plurality of taps, a pair of ratio adjuster switches for selectively making connection to said taps, a terminal for said winding, a pair of transfer switches connected to said terminal, a split reactor each half of which is serially connected between a different ratio adjuster and a different transfer switch, an insulating transformer, a disconnecting switch for connecting the primary winding of said insulating transformer across said transfer switches in series, an arcing contactor connected across the secondary winding of said insulating transformer, and means for permanently grounding the secondary winding circuit of said insulating transformer.

3. In combination, a transformer having a winding, said winding having a plurality of taps, a pair of liquid break ratio adjuster switches for selectively making connection with said taps, a terminal for said winding, a pair of liquid break transfer switches connected to said terminal, a split reactor each half of which is serially connected between a different ratio adjuster and a different transfer switch, an insulating transformer, a liquid break disconnecting switch for connecting the primary winding of said insulating transformer across said transfer switches in series, and an air break arcing contactor connected across the secondary winding of said insulating transformer.

4. A load-ratio-control system comprising in combination a multi-tapped transformer winding, a pair of ratio adjuster switches for selectively making connection with the taps of said winding, a pair of transfer switches having a common connection to a line terminal for said winding, a split reactor one-half of which is serially connected between one ratio adjuster switch and one transfer switch and the other half of which is serially connected between the other ratio adjuster switch and the other transfer switch, a switch connected across both transfer switches, an insulating transformer, a switch for connecting the primary winding of said insulating transformer across both transfer switches, and an arcing contactor connected to short-circuit the secondary winding of said insulating transformer.

5. A load-ratio-control system comprising in combination a multi-tapped transformer winding, a pair of liquid break ratio adjuster switches for selectively making connection to the taps of said winding, a pair of liquid break transfer switches having a common connection to a line terminal for said winding, a split reactor one-half of which is serially connected between one ratio adjuster and one transfer switch and the other half of which is serially connected between the other ratio adjuster switch and the other transfer switch, a normally closed switch connected across both of said transfer switches in series, an insulating transformer, a liquid break disconnecting switch for connecting the primary winding of said insulating transformer across both of said transfer switches in series, an air break arcing duty contactor connected to short-circuit the secondary winding of said insulating transformer, and a permanent ground connec-

tion for the secondary winding of said insulating transformer.

6. An arc ing duty switching arrangement for a load-ratio-control system comprising in combination an insulating transformer, a switch for connecting the primary winding of said transformer between two points in said system, an arc ing duty switch connected across the secondary winding of said transformer, a third switch connected directly between said two points, and interlocking operating means whereby said switches are opened sequentially in the inverse order mentioned and are closed sequentially in the opposite order.

7. In a load-ratio-control system, a pair of points between which an electric current is to be interrupted, a normally closed switch interconnecting said points, an insulating transformer, a second normally closed switch connected across the secondary winding of said transformer, a third normally closed switch connected in series with the primary winding of said transformer between said points, and means for opening said switches in the order mentioned and for closing them in the reverse order.

15

8. In a load-ratio-control system, a pair of points between which an electric current is to be interrupted, a normally closed switch interconnecting said points, an insulating transformer, a

5 second normally closed switch connected across the secondary winding of said transformer, means for permanently grounding one terminal of said secondary winding, a third normally closed switch connected in series with the primary winding of said transformer between said points, and means for opening said switches in the order mentioned and for closing them in the reverse order.
